ROBERT L. HOLLIDAY, OF NEW YORK, N. Y., ASSIGNOR, BY MESNE ASSIGNMENTS, TO COLGATE-PALMOLIVE-PEET COMPANY, OF CHICAGO, ILLINOIS, A CORPORATION OF DELAWARE, AND THE PROCTER & GAMBLE COMPANY, OF CINCINNATI, OHIO, A CORPORATION OF OHIO

MANUFACTURE OF SOAP POWDER

Application filed April 19, 1926. Serial No. 102,861.

The present invention relates to the manufacture of a soap powder product containing soda ash, or the like, and has to do particularly with the manufacture of the dry product by a method radically different from the common methods heretofore employed in the commercial production of this type of product, and by a method which permits of systematic and accurate control of the conditions of the process at all times.

Soap powders or washing powders, as distinguished from ordinary soap produced in powdered form, contain a certain quantity of soda ash (sodium carbonate). Such soap powders are mixtures of soda ash, soap and water. The type of soap powder in general use at the present time contains usually from 30% to 40% of water. In the ordinary process of manufacture the soda ash is added to the hot soap stock and the water content of the mixture is controlled until the desired proportion of ingredients is attained. The hot mixture is then chilled by spreading it upon refrigerating cylinders or rolls through which a cold liquid such as brine is circulating. The chilling action of the cold rolls effects a certain crystallization of the sodium carbonate with an amount of the water incorporated into the crystals as water of crystallization. The resulting product as scraped from the rolls is intended to be solidified and friable and is subjected to a breaking up and aerating operation, as by shovelling over manually, to reduce it to a reasonably finely divided form for marketing as a soap powder. The reduction of the hot liquid mixture to solidified form upon the chilling rolls is essentially a crystallization and hydration operation as distinguished from drying by evaporation. The cooling of the mixture creates a condition favorable to the crystallization of the sodium carbonate and, as the sodium carbonate crystallizes, it incorporates as water of crystallization the major portion of water in the batch.

It has also been proposed to produce soap powder of this type by disintegrating the usual hot soap and soda ash mixture and subjecting it while in such disintegrated condition to the action of a cooling gas wherein the particles

are cooled below the temperature of crystallization of the sodium carbonate ingredient and are thus reduced to the form of solidified particles or fragments. The action which takes place is a crystallizing and hydrating action in all respects similar to that which occurs in the usual operation of reducing the mixture to solid form by the cold roll process. The cooling or chilling agent which is employed is refrigerated air or, in certain instances, untreated atmospheric air if atmospheric conditions of temperature and humidity happen to be favorable. In these processes of reducing the soap and soda ash mixture to solid form by cooling to effect crystallization, a slight amount of evaporation occurs incidentally by reason of the contained heat in the soap mixture and by reason of the fact that the chilling air or the atmosphere surrounding the chilling rolls takes up a small amount of the water present in the material. The amount of evaporation which takes place is small and is largely dependent upon the particular atmospheric conditions which prevail at the time the process is being carried out. An evaporation of from about 2% to 5% or less calculated on the weight of the mixture about represents the range of conditions usually encountered in commercial operation. The "old style" soap powders were sometimes made by a process which involved a certain drying of the product to produce it with a low water content. It has also been proposed as a matter of theory to produce soap powder by spraying a hot liquid soap and soda ash mixture into atmosphere or into a heated chamber in the manner previously proposed for producing powdered soap, but such a process cannot be successfully conducted due to impossibility of solidifying the product with a proper water content, absence of control of humidity conditions, effect of atmospheric conditions, and the like, and, as far as I am aware, such a process has never been employed in the production of the commercial product.

The present invention is in part based upon the discovery that soap powder, that is, a powdered soap product consisting of a mixture of soap, soda ash and water can, in fact, be

produced by preparing a fluid mixture of the ingredients and evaporating a portion of the water from it in a particular manner, and it is an object of the present invention to provide such a process wherein a soap powder is produced by evaporating a portion of its water content by means of heat, conducting off the removed moisture, and controlling the conditions of evaporation to produce a uniform high water content product as desired. By the present process a soap powder product possessing all of the characteristic and advantageous properties ordinarily possessed by products of this class and having certain additional desirable properties, such as greater ease of solubility, and the like, may be easily and conveniently produced throughout the entire range of moisture content required in the commercial powder product. The soap and soda ash mixture is preferably prepared with an excess of water. It is prepared in such condition that it is free flowing and is capable of being broken up into small uniform liquid drops by spraying in the manner above described. In the ordinary process of manufacture the soda ash and soap mixture before chilling is a paste which may contain say 43% by weight of water. A small amount of this water is evaporated incidentally during the manufacturing operations so that the ultimate product may contain say 40% of water. A very important practical difficulty is presented by the fact that, in order to obtain the ultimate product in a solidified condition which will retain its powder form at all satisfactorily, the mixture before chilling must be so restricted in water content as to be very difficult of handling in pipe lines and the like. Much trouble is experienced through solidification of the original mixture in the pipe lines and tanks. When the initial mixture is of a consistency which permits handling of it at all, much difficulty is encountered in getting the material to assume solid form as it comes out of the chilling process. In warm weather when the humidity is high it is often extremely difficult to accomplish the solidification of the product to such extent that it may be used commercially. The process of the present invention, however, provides for the compounding of the initial mixture in such proportions as to render it perfectly fluent and easy of handling, evaporating out of it by means of applied heat any desired amount of water to thereby directly produce an apparently dry soap powder of any desired water content which will permit the product to be in solid form, the water content of the material being to a considerable extent absorbed into the product as water of crystallization in the sodium carbonate constituent. The essential features of the process are the proper breaking up of the initial mixture into liquid drops of appropriate size and form, the evaporation of these drops

of material to the desired extent by a heated drying gas, the maintaining of proper conditions, controlling of the evaporation so that the particles of material are produced with a proper water content, and the collection of the solidified particles under appropriate conditions of humidity and temperature. These essential features are accompanied by the advantages and results arising out of the process, such as the possibility of preparing the initial mixture in condition sufficiently fluid to avoid all troubles of piping and handling, accurate control of the amount of moisture in the ultimate product independently of atmospheric conditions, and the like. The requisite control in the drying of the product is accomplished by drying the mixture in a gaseous drying medium.

It is important that the particles of soap powder stock be treated in a current of circulating gas which carries away the moisture evaporated from the particles and flows in such fashion that, when continued operation of the apparatus has been established, the conditions of the process such as humidity, temperature, state of dryness of the soap powder particles, etc., at any given place in the drying tower are, for all practical purposes, substantially constant. It is also important that the current of gas in which the soap powder particles are treated be passed through the drying tower in a common direction of flow with the particles so that the particles are carried in and by the gas current and are thus positively propelled through and out of the apparatus in a definite and regular manner. With this arrangement the gas first contacts with the particles at substantially its highest temperature and last contacts with the solidified soap powder particles at substantially its lowest temperature. The particles under treatment are carried through the tower in a positive flow, and thus all of the particles remain in the drying tower for substantially the same length of time and are subjected to substantially identical treatment. With this condition existing the air current may be controlled and conditioned as to rate of flow, volume, temperature, moisture content, and the like, so that any desired variations in the ultimate product may be obtained by variation of one or all of these variables. The process also provides for removing the treated soap powder particles together with the gas which carries them, as well as the moisture contained in it, from the drying tower in intermixed condition so that collection of the dried particles may proceed as desired at a point removed from the hot drying tower. The collection problem is simplified by reason of the fact that all of the solids may pass out of the drying tower at one point. In the matter of conditioning the air current in which the soap powder particles are carried in suspension cooling gas may be admitted

as desired along the length of the tower so that after the particles have been reduced to a desired moisture content they may also be suitably reduced in temperature to assure their production in non-sticking form whereby the soap powder product will be a finely divided regular apparently dry free flowing powder. The present process therefore provides for a uniform treatment of the particles of soap powder stock to produce a uniform product which may be controlled to possess within reasonable limits any desired moisture content and which may be successfully and easily produced commercially at all times and in all weather conditions in the form of an apparently dry solid easily handled powder product.

The accompanying drawing illustrates more or less diagrammatically an apparatus in which the present process may be carried out as a continuous operation requiring but a very small proportion of the labor required in the present commercial processes of manufacturing soap powder. The powder stock, after having been produced in the usual course of the manufacture of the product and having been prepared with a sufficient amount of water to adapt it for treatment by the present process, is delivered to a tank 1 provided with an agitator 2 driven continuously by motor 3 for the purpose of maintaining the entire body of stock in a thoroughly mixed homogeneous condition. The tank 1 is steam jacketed as indicated at 4 for the purpose of maintaining the stock at a suitable temperature. The liquid stock from the tank 1 is passed through line 5 into the drying tower 6. The breaking up or spraying of the liquid stock into the form of small uniformly constituted particles is effected by means of spray nozzles 7 located in the upper part of the drying tower 6 and arranged about the tower in such fashion as to uniformly distribute the spray throughout the entire upper portion of the tower. In the apparatus here shown the flow of soap to the nozzles 7 occurs due to gravity, and the breaking up of the material into the form of a spray is effected by means of atomizing air or steam supplied to the nozzles 7 as indicated at 8. The drying gas consists of atmospheric air which is heated in the furnace 9 and is then passed into the upper portion of the drying tower 6 through a passage or duct 10. The furnace 9 may, for instance, be oil fired and the air passing through it may be heated by causing it to pass along one side of heat transferring surfaces which on the other side are heated by direct contact with the products of combustion. The heated air entering the upper portion of the tower contacts with the atomized soap liquid issuing from the spray nozzles 7 at substantially its hottest temperature and, while drying 60 of the soap powder particles is taking place,

the drying air, the particles entrained therein and the moisture absorbed in the air pass downwardly through the drying tower in a common direction of flow and pass out of the tower at the discharge opening 11 in intermixed condition. This discharge stream of material passes through duct 12 into collector 13, here shown as an ordinary cyclone collector, wherein the collected solids are discharged through the hopper 14, and the effluent gas passes out through the duct 15. The residual solids entrained in the gas issuing from collector 13 are collected in bag collectors 16, the solids being discharged through the hoppers 17 at the bottom of the collectors. A conveyor 18, which may be a screw conveyor, a pneumatic conveyor, or the like, is provided to receive the solids coming from the collectors and convey them continuously into the barrel or other package or storage reservoir 19. The flow through the entire apparatus is established by means of a motor operated fan 20 positioned at the discharge side of the bag collector 16 and passing the gas drawn from the collectors to atmosphere through stack 21.

The particles of the sprayed liquid are carried in positive flow through the tower 6 by the drying gas, and thus every particle is subjected to the drying treatment for substantially the same length of time. Conditions in the tower are controlled by regulating the temperature and amount of the soap and soda ash material passed into the tower and the temperature and amount of drying air supplied to the tower. This, together with the concurrent flow of materials through the tower, effects a positive control of temperature and humidity conditions in the tower and permits the production of a uniform product of any desired moisture content. To further control the temperature conditions in the tower and particularly to restrict the evaporating action at the point where the moisture content of the soap particles has been reduced to a desired amount and for the purpose of cooling the dried particles to such extent as to render their collection in dry powder form feasible, a supply of cooling air may be admitted to the tower as indicated at 22. The tower may be designed for the admission of this cooling air at any one or more points along the length of the tower and, by way of example in the apparatus here shown, the cooling air is admitted near the bottom of the tower and consists of atmospheric air introduced by means of the power driven blower 23. In some instances it may be feasible to condition this air as, for instance, by heating to a certain degree before admitting it to the tower. At the bottom of the tower 6 below the discharge opening 11 is a motor driven disintegrator 24 designed to receive any agglomerates or heavy particles which may possibly be

formed in commercial operation. Such heavy particles will not be drawn into the duct 11 but will drop into the disintegrator 24 where they will be immediately broken up and caught in the air current which is drawn into the disintegrator through the opening 25. This apparatus furnishes a means for carrying out the present process as a continuous operation which requires no manual handling of the material from the initial raw stock to the finished powder product and, for that matter, to package form ready for shipping.

As an instance of a specific embodiment of the present process which has been successfully employed in the production on a commercial scale of a soap powder containing soda ash, the following conditions are given: The soap, soda ash, and water mixture was made up in such condition that it was sufficiently liquid to flow readily and to be properly disintegrated by spraying. The mixture contained about 13% of soap solids, 61% of water and 26% of dry sodium carbonate. This gave a mixture having a total solid content of about 39% or 40%, and a corresponding water content of about 60%. Operation with as low as say 50% of water is possible. In preparing the mixture the sodium carbonate was reduced to solution in hot water, and the hot soap stock in liquid or paste condition was mixed with it. This procedure has a distinct advantage over the procedure now used in the commercial manufacture of soap powders wherein the soda ash is to a large extent added to the liquid soap stock in powder form for the reason that if added in the form of a solution the resulting mixture would contain a prohibitively high water content. This procedure avoids many important practical difficulties such as necessity of grinding the soda ash, handling and transportation of the bags of dry soda ash, and the like. With the present process the soda ash as received in the plant may immediately be thrown into a dissolving vat and the resulting soda ash solution piped and pumped to any part of the plant where it is needed. The soap stock used in the preparation of the soap powder mixture contained about 33% water so that the soap powder mixture as sprayed contained about 20% of soap stock, 26% of soda ash, and 54% of additional water. This stock was preheated to a temperature of about 180° F., and supplied to the spray nozzles from a tank in which the material was under constant agitation to maintain a homogeneous and uniform mixture. Spraying was accomplished by an atomizer. The initial temperature of the dry air was 150° F., and the temperature after the drying treatment had been complete was about 100° or 110° F.; that is, almost atmospheric temperature. Initial temperatures of as high as 300° F. have been success-

fully used, and temperatures considerably in excess of the figure may be employed.

The soap powder product produced under the conditions just stated is a fairly light bulking free flowing apparently dry powder. The product is very uniform in appearance and in texture. This uniformity and fineness of particle size is particularly evident upon comparing the product with soap powders of this type now available on the market. The product is soft to the feel, goes into solution in water with a very small amount of stirring or agitation and floats on the surface when a mass of the powder is dropped into a receptacle containing water. When some of the powder product is compacted as by squeezing in the hand and is then introduced into water it quickly disintegrates or spreads out upon the water and dissolves. This is in contrast to ordinary commercial soap powders which when compacted in this way and placed in water retain their lump form and in the washing process act substantially like solid lumps of soap. The product obtained under the conditions just noted contained about 30% of moisture. The moisture content may be easily varied by varying the conditions of the process. For instance, a product ranging in moisture content from 4% to 40% may be produced by simple variations in the amounts of liquid and air and the temperature of the air. It will be understood that the moisture content depends not only upon the temperature differential along the length of the tower but upon the relative amounts of drying air and liquid which are supplied to the tower, the temperature to which the liquid is pre-heated, and the like. Starting with a stock having a 60% water content and finishing with a product having a 40% water content, these proportions being based respectively on the weights of the stock and of the finished product, represents an evaporation equal to about 33% of the weight of liquid stock and about 55% of the total water content of the original stock. This is a reasonable figure for practical operation, and in any event evaporation of say 30% of the total water content is desirable.

The particles of the soap powder product as they appear under the microscope are of generally spherical shape. They are sufficiently stable to retain their shape during handling, and the spherical shape renders the product free flowing. In contrast to the continuous amorphous structure of the powdered soap particles the particles of the soap powder are distinctly granular in nature. This granular structure is apparent from the external appearance of the magnified product. When the product is disintegrated under the microscope it breaks up into its component grains and this granular structure is evident down to the smallest particles of the material which can be distinguished under

a high magnification, as for instance 500 diameters. When the product is brought into contact with water under the microscope each individual particle rapidly and easily dissolves merely by the contact of the water with it. Mechanical disintegration of the particles into their component parts to effect solution is not necessary. As long as the particle contacts with water it dissolves rapidly, retaining its spherical form until it is completely dissolved. This action explains the ability of the product to go rapidly and easily into solution in water. The granular nature of the particles is probably due to the tendency of the soda ash ingredient of the powder to crystallize. The major part of the moisture content in the product probably occurs in the nature of water of crystallization in the soda ash ingredient, and it is therefore desirable to encourage the granular or crystalline structure in the particle for the purpose of facilitating incorporation into the product of a large percentage of water. This composite granular structure of the soap powder particles is in marked contrast to the continuous amorphous structure of the particles of the powdered soap product wherein no soda ash is present.

The present invention makes possible the reduction of the initial soap and soda ash mixture to the form of a free flowing liquid which may readily be pumped and conveyed through pipe lines without danger of solidification. In the ordinary commercial processes of soap powder manufacture the initial stock is very heavy and much difficulty is encountered due to its solidification. The present invention involves the provision of heated drying air. When atmospheric conditions are favorable soap powder stock may be solidified by passing it through atmospheric air but with the range of atmospheric conditions encountered in most localities the air is often too humid to permit successful production of the soap powder in this manner. The present invention makes possible the use of a free flowing liquid stock, makes possible the use of high temperature drying air which is the economical way of removing moisture and also makes possible the creation of conditions in the drying tower which are favorable for solidification of the soap powder with a high water content. This is done by spraying into the high temperature air a large quantity of the free flowing liquid stock so that the initial evaporation which occurs upon contact of the liquid spray with the heated air rapidly reduces the temperature of the air and increases its humidity so that favorable conditions are established. With this type of operation a large output of soap powder is obtained by the use of a relatively small quantity of air so that the amount of air which must be handled by the fan and the collecting system is minimized. This proc-

ess, therefore, possesses the important advantages of economy in evaporating costs, a free flowing initial liquid stock and a relatively small quantity of air through the fan and collectors per unit output of product.

The present invention provides a practical process for producing soap powder on a commercial basis in continuous operation and with a total cost of operation and labor which is but a fraction of that involved in the ordinary commercial methods. The process makes possible the control of the conditions to which the material is subjected so that a uniform product of desired character may be obtained. The process is flexible in the sense that different sets of conditions can be established in continuous operation to thereby produce products of different character as, for instance, of different water contents. The treatment of the product involves the evaporation of a substantial amount of water from the initial stock, and the water thus evaporated is carried away so that substantially constant conditions of humidity and partial vapor pressures in the treating gas are maintained at any part of the apparatus. The product produced by the present process exhibits certain well-defined advantages over the ordinary soap powders, such as easier and more rapidly solubility, freedom from lumping or caking in water, uniformity in texture and particle form, and the like. The invention contemplates both the process and the product.

The expression in each claim, calling for the effecting removal of a portion of the moisture content of the sprayed powder mixture down to substantially 40% by bringing a current of heated moisture absorbing treating gas into contact with the sprayed particles of the said mixture, is employed to define the removal of a portion of the moisture content from a degree above 40% to substantially 40% or lower, but is intended to be limited to a percentage as high as that required in the production of a relatively high moisture containing soap powder as distinguished from the moisture content of spray dried soap such as that disclosed in applicant's Reissue Patent 16,749, which usually contains from 3% to about 10% in the final product.

I claim:

1. The process of producing a dry appearing relatively high water containing soap powder product consisting mainly of soap and soda ash with the soda ash in a predominating amount, which comprises preparing a soap and soda ash mixture with an amount of water sufficient to dissolve substantially all of the soda ash ingredient, the proportion of water being substantially in excess of the amount desired in the finished product so as to render the mixture free flowing to permit its being broken up into liquid drops by spraying and permitting its being handled

through pumps and pipe lines with ordinary care without danger of solidification therein, spraying said soap powder mixture to thus subdivide it into drops, effecting removal of 5 a portion of the moisture content of the sprayed soap powder mixture down to substantially 40% by bringing a current of heated moisture absorbing treating gas into contact with the sprayed particles of the said 10 mixture, regulating the total moisture absorbing capacity of the treating gas relative to the total amount of water desired to be removed from the product being treated to thereby inhibit the removal of moisture from 15 said particles of sprayed soap powder mixture while the said mixture still has a relatively high water content, effecting incorporation of a major portion of said relatively high water content with the other constituents 20 of the said soap powder mixture as water of crystallization to produce an ultimate product in apparently dry powder form by continuing the treatment of the sprayed soap powder mixture having said relatively 25 high water content in a treating gas of controlled low moisture absorbing capacity until the said sprayed material under treatment has assumed an apparently dry condition, and then separating the apparently dry 30 powder product from the treating gas to constitute the finished product.

2. The process of producing a dry appearing relatively high water containing soap powder product consisting mainly of soap 35 and soda ash with the soda ash in a predominating amount, which comprises preparing a soap and soda ash mixture with an amount of water sufficient to dissolve substantially all of the soda ash ingredient, the proportion 40 of water being substantially in excess of the amount desired in the finished product so as to render the mixture free flowing to permit its being broken up into liquid drops by spraying and permitting its being handled 45 through pumps and pipe lines with ordinary care without danger of solidification therein, spraying said soap powder mixture to thus subdivide it into drops, effecting removal of a portion of the moisture content of the 50 sprayed soap powder mixture down to substantially 40% by bringing a current of heated moisture absorbing treating gas into contact with the sprayed particles of the said mixture in such manner that the said gas surrounds the sprayed drops absorbing moisture therefrom and entrains said drops and carries them along in concurrent flow while the said water absorbing action takes place, regulating the total moisture absorbing capacity 55 of the treating gas relative to the total amount of water desired to be removed from the product being treated to thereby inhibit the removal of moisture from said particles of sprayed soap powder mixture while the 60 said mixture still has a relatively high water

content, effecting incorporation of a major portion of said relatively high water content with the other constituents of the said soap powder mixture as water of crystallization to produce an ultimate product in apparently 70 dry powder form by continuing the treatment of the sprayed soap powder mixture having said relatively high water content in the current of treating gas of controlled low moisture absorbing capacity, the sprayed material being carried in suspension in said current of treating gas and in concurrent flow therewith until the said sprayed material under treatment has assumed an apparently dry condition, and then separating the apparently dry powder product from the treating gas to constitute the finished product.

In testimony whereof I affix my signature.
